ABSTRACT OF THE DISCLOSURE

A tubing paraffin scraper having a mandrel with a central bore communicating with an open chamber defined in the bottom of the mandrel of a diameter greater than the bore. A free ball is contained in the chamber and is movable between two positions to act as a valve. A pair of parallel bars are disposed across the bottom of the chamber in order to retain the ball therein, and yet allow flow of fluid through the chamber. External rings are mounted about the mandrel and have a diameter sufficient to clear the interior walls of the tubing of paraffin. During the free ascent of the scraper up the tubing, paraffin is scraped from the tubing and accumulated within the central bore of the mandrel. At the top of the tubing the accumulated paraffin is exhausted through the end of the open chamber.

Field of the invention

This invention relates to paraffin scrapers, and more particularly to free piston type paraffin scrapers which freely ascend and descend within the well tubing.

The prior art

The deposit of paraffin upon the interior walls of oil well tubing during the flowing of oil is a serious problem. Many different types of paraffin scrapers have thus been heretofore devised which scrape accumulated paraffin from oil well tubing walls. The free piston, or "rabbit," type of paraffin scraper has been found to be particularly useful to clean off the walls of well tubings, as these scrapers automatically ascend and descend in the tubing with the pumping of each head of well fluid to remove accumulated paraffin. The free piston scrapers have also heretofore been found useful in sealing with the walls of the tubing to assist in the production of well fluids by means of gas lift.

In order to provide a free piston action for a paraffin scraper within a well tubing, many of the paraffin scrapers heretofore developed have included various types of valves for blocking interior scraper passages so that the scrapers are forced upwardly when oil is flowing from the well. Paraffin is removed from the tubing walls and forced out of the pipeline outlet by ascent of the scraper. The valves are then opened after the scraper reaches the top of the wall to let the scraper slowly descend under its own weight. Examples of such paraffin scrapers are disclosed and described in U.S. Patent No. 2,058,825, U.S. Patent No. 2,893,493, and U.S. Patent No. 3,058,525.

The performance of piston paraffin scrapers heretofore developed has not been completely satisfactory due to the fact that the scrapers merely tend to move the paraffin scraped from the tubing walls upwardly and outwardly through the top of the tubing. Such large amounts of paraffin are sometimes removed by these scrapers that the performance of the scraping action is sometimes impeded, and portions of the removed paraffin sometimes tend to leak downwardly past the ascending scraper. Further, the valves utilized by paraffin scrapers heretofore developed have not always been satisfactory with respect to long periods of operation, as the valves are complex in con-

2

struction and tend to wear and easily clog with accumulated paraffin.

Summary

In accordance with the present invention, a free piston paraffin scraper includes a mandrel having a bore through the length thereof which communicates at a transition portion with an open bottom chamber having dimensions greater than the bore. A ball is disposed in the chamber movable between two positions and sized to seat on the transition portion in one position. A stop device is mounted in the bottom of the chamber to retain the ball within the chamber when the ball is in a second position. An external ring is connected about the mandrel and has a diameter sufficient to clear the interior walls of a well pipe of accumulated paraffin.

The drawings

For a more complete understanding of the present invention and for further objects and advantages thereof, reference may now be had to the following description taken in conjunction with the accompanying drawings in which:

FIGURE 1 illustrates a well pipe with the present paraffin scraper located in the bottom regions thereof;

FIGURE 2 illustrates a cross sectional view of the present paraffin scraper; and

FIGURE 3 illustrates a sectional view of the paraffin scraper shown in FIGURE 2 taken generally along the lines 3—3.

The preferred embodiment

Referring to FIGURE 1, a conventional oil well tubing 10 extends for a distance above the surface of the ground and includes a rubber-filled bull plug 12 at the upper end thereof. An outlet pipe 14 allows the flow of oil from the tubing 10 to suitable processing and storage stations. A valve 16 in the outlet pipe 14 is controlled by a motor valve 18 in order to selectively initiate or stop the flow of oil from the tubing. A manual valve 20 is also provided in order to allow manual regulation of the flow of oil.

A paraffin scraper designated generally by the numeral 22 is illustrated in the bottom regions of the tubing 10 resting upon a collar stop 24. A pair of scraping rings 26 and 28 are connected about the paraffin scraper 22 and are of diameters so as to fit closely within the tubing 10 without impeding movement of the scraper.

FIGURE 2 illustrates a detailed sectional view of the paraffin scraper 22. The scraper 22 comprises an elongated metal mandrel 30 having a central bore 32 along the length thereof. The central bore 32 communicates at an annular transition portion 34 with an enlarged diameter open end chamber 36. Chamber 36 encloses a free ball 38 which is adapted to act as a valve by sealingly seating against the transition portion 34. The ball 38 is heavier than a like volume of borehole fluid and is preferably constructed from material such as oil resistant rubber or plastic in order to resist the high temperatures and well bore fluids of the well.

As may be most clearly seen in FIGURE 3, a pair of parallel pins 40 and 42 are connected across the lower part of chamber 36 to retain ball 38 within the chamber. Of course, it will be apparent that a number of different retaining devices could be utilized to retain the ball within the chamber in place of the pins 40 and 42, as for instance a large mesh wire screen or the like.

The mandrel 30 also includes in its lower end a nose section 44 which is tapered to facilitate the passage of the scraper downwardly through the tubing 10. The nose section serves to guide the paraffin cutter back into the well tubing after the cutter has risen to the well head. The nose section 44 is constructed from resilient material to cushion the impact when the paraffin scraper comes to

rest against the collar stop 24. The nose section 44 also includes a central bore 46 which communicates at one end with the chamber 36. Suitable fastening pins 48 attach the nose section 44 to the lower end of the mandrel 30. If desired, the nose section 44 may be replaced by tapering the lower end of the mandrel 30.

The upper end of the mandrel 30 is annularly relieved to define a fishing neck 50 which allows the scraper to be retrieved from a well tubing 10 by suitable fishing devices. The outside diameter of the fishing neck is slightly less than the overall diameter of the mandrel 30 to facilitate the passage of paraffin removed by the ring 28 into the bore 32. An upper portion 52 of the bore 32 is conically shaped in order to facilitate the entry of the paraffin into the bore 32.

In operation of the paraffin scraper, the valves 16 and 20 are closed, the upper portion of the tubing 10 is removed, and the paraffin scraper 22 is dropped into the tubing. The valve 20 is then opened to allow the paraffin scraper 22 to slowly sink toward the bottom of the tubing 10 under its own weight.

The descent of the scraper will be relatively slow, due to intermittent valving action of the ball 38 within the chamber 36. When the downward speed of the paraffin scraper becomes excessively rapid, the ball 38 will be seated against the transition portion 34 by the force of the fluid passing through the bore 46, the chamber 36 and the bore 32, thereby temporarily arresting the downward movement of the paraffin scraper 22. After the motion of the paraffin scraper 22 has been substantially reduced, the ball 38 will fall under its own weight to the position illustrated in FIGURE 2, thereby again allowing passage of the borehole fluids through the interior of the paraffin scraper 22 and allowing the paraffin scraper 22 to further descend within the tubing 10. The paraffin scraper 22 will thus slowly descend downwardly in the tubing 10 until it comes in contact with the collar stop 24. At such depths, the pressure and heat upon the paraffin scraper 22 will melt off any paraffin which has accumulated upon the tool during its descent.

When it is desired to flow oil from the tubing, the valve 16 is opened to allow flow of oil through the outlet pipe 14. The force of the fluid flow will force the ball 38 upwardly to seat against the transition portion 34. The force of the fluid flow will thus push the paraffin scraper 22 upwardly along the tubing 10. Due to the close fit of the rings 26 and 28, the paraffin which has accumulated upon the interior walls of the tubing 10 will be removed.

Some of the paraffin removed by the rings 26 and 28 will be forced ahead of the upwardly moving paraffin scraper 22, while a portion of the removed paraffin will enter the bore 32 through the conical entrance 52 of the mandrel 30. A quantity of paraffin will thus be accumulated within the bore 32 during the ascent of the paraffin scraper 22, thereby preventing amounts of the paraffin scraped from the walls from passing between the rings 26 and 28 and the interior walls of the tubing 10 and escaping below the ascending paraffin scraper 22. For some applications, it may be desirable to combine rings 26 and 28 into an elongated single ring about mandrel 30.

The paraffin scraper 22 will continue to ascend as long as the valve 16 is open until the top of the paraffin scraper 22 comes in contact with the resilient ball plug 12. The ball plug is rubber-filled in order to cushion the impact of the paraffin scraper 22. After the scraper 22 comes to rest against ball plug 12, the ball 38 will fall downwardly against pins 40 and 42, thereby opening the lower end of bore 32. Pins 40 and 42 are spaced above the opening to bore 46 so that ball 38 cannot block 46 when in its downward position.

The length of the paraffin scraper 22 is such that the nose section 44 will be disposed in the region of the open-

ing to the outlet pipe 14. The passage of the borehole fluid past the end of the nose section 44 and through the outlet pipe 14 creates a suction in the bore 46, thereby tending to exhaust the accumulated paraffin within the bore 32 from the paraffin scraper. The accumulated paraffin within the bore 32 is then swept outwardly through the outlet pipe 14 by the flow of fluid.

After the accumulated paraffin within the bore 32 has been exhausted and the desired amount of borehole fluid has been flowed out of the tubing 10, the valve 16 will be shut and the paraffin scraper 22 will again begin its free descent downwardly to the lower regions of the tubing 10.

Whereas the present specification has been described in detail with respect to a certain embodiment, it will be understood that variations and modifications may be suggested to persons skilled in the art which will not depart from the scope of the invention as defined in the appended claims.

What is claimed is:

1. A free piston paraffin scraper for well tubing comprising:

- (a) a mandrel having a bore through the length thereof communicating at the lower end thereof at a transition portion with an open bottom chamber which has a diameter larger than said bore, said bore having an open upper end shaped to receive paraffin scraped from the walls of the well tubing when said mandrel moves upwardly in the well tubing,
- (b) a ball having a weight heavier than a like volume of borehole fluid disposed within said chamber for free unimpeded movement within the said chamber between upper and lower positions, said ball adapted to seat on said transition portion in the upper position to cause upward movement of said mandrel in the well tubing,
- (c) at least one bar extending across a lower part of said chamber for maintaining space between said ball and said open bottom to allow fluid flow through said bore when the ball is in the lower position,
- (d) a generally resilient nose cone portion on the lower end of said mandrel with a bore therethrough, and
- (e) external ring means connected about said mandrel and having a diameter to clear the interior walls of the well tubing of paraffin when said mandrel moves upwardly in the well tubing, whereby paraffin is collected by the open upper end of said mandrel and maintained within said bore during the upward ascent of said mandrel and wherein the paraffin is exhausted from the lower end of said mandrel when said mandrel reaches the top of said well tubing and said ball is in the lower position.

2. The paraffin scraper of claim 1 wherein the open upper end of said bore has a conical shape with the major opening upward in order to receive paraffin collected by said scraper.

3. The paraffin scraper of claim 1 and further comprising:

- a pair of parallel bars in said chamber spaced apart for a distance less than the diameter of said ball.
